UNITED STATES PATENT OFFICE.

JOHN ZOTKIEWICZ, OF MOUNT CARMEL, PENNSYLVANIA.

RAIL-FASTENING MEANS.

1,408,058.

Specification of Letters Patent. Patented Feb. 28, 1922.

Application filed November 28, 1921. Serial No. 518,235.

To all whom it may concern:

Be it known that I, JOHN ZOTKIEWICZ, a citizen of Poland, residing at Mount Carmel, in the county of Northumberland and State 5 of Pennsylvania, have invented certain new and useful Improvements in Rail-Fastening Means, of which the following is a specification.

This invention relates to a means for 10 securing the rails of railroad tracks to the ties, or sleepers, the invention having for an object to provide a simple and efficient means for this purpose which functions without the use of spikes, permitting of ready removal 15 and replacing of the rails when necessary.

For further comprehension of the invention, and of the objects and advantages thereof, reference will be had to the following description and accompanying drawings, and to the appended claims in which the various novel features of the invention 20 are more particularly set forth.

Fig. 1 of the drawings is a plan view with one of the rails in horizontal section on the 25 line 1—1 of Fig. 2, of a rail fastening means embodying the invention.

Fig. 2 is a vertical sectional view taken 30 transversely of the track showing the device itself in elevation.

Fig. 3 is an elevation of the device, taken transversely of the track, part of the sleeper element being shown in longitudinal section.

Fig. 4 is an underside plan view of the 35 rail engaging latch with its supporting and operating parts, the sleeper element not being shown.

Referring now to the drawings, the reference numeral 10 indicates portions of a pair of track rails. These rails rest on opposite 40 ends of a metal tie-bar 12 provided at its extremities with backwardly projecting flanges 13 which fit closely over the base-flanges of the rails on the outer sides thereof. This tie-bar has integral bosses 14 on its 45 underside at opposite ends which are adapted to be set in a concrete base or sleeper element 15 on which the tie-bar rests.

The upper face of the tie-bar 12 is recessed or cut away throughout the major portion of 50 its length, leaving thickened ends 12' on which the rails 10 rest. This recess is filled by a supplementary strip 18 which latter is recessed on its underside as at 19. This strip 18 is secured upon the bar 12 by means of 55 nuts 20 threaded upon bolts 21 fixed to and projecting upward from the bar, these bolts

passing upward through suitable openings, surrounded by downwardly projecting flanges 22, in the strips 18.

The strip 18 has pivotally mounted on opposite ends thereof a pair of latch elements each in the form of a short bar 25 having its outer end shaped to fit over the base flange of the rail on the inner side of the latter. The latch 25 is fixed on the upper 60 end of a vertical stud 26 suitably pivoted in the strip 18, this stud having fixed on its lower end, within the recess 19, a worm gear 27 which is engaged by a worn pinion 28 having trunnion elements suitably supported by 65 brackets 29 fixed to the under face of the strip in the recess. One of these trunnion elements, 30, is extended through an opening in the side wall of the recess 19 and is squared to receive a suitable wrench or spanner for turning purposes. The latch 25 is 70 preferably arranged to cause the end thereof to jam against the web of the rail to hold the latter securely locked, one corner of the latch being rounded as at 25' to enable it 75 to clear the flange of the rail when the latch is being moved to locking position.

I also preferably provide a means, operated by the stud 26, for locking the ends of the strip 18 to the thickened ends 12' of the 80 bar 12. This means comprises for each end of the strip a bolt 32 slidably carried in the end thereof and adapted to engage in a socket 33 in the bar end 12', this bolt being 85 normally urged to retracted position by means of a coiled expansion spring 34 which surrounds it. Upon the upper face of gear 27 a cam boss 35 is formed and is adapted to engage the inner end of the bolt 32 to move the latter into the socket 33 when the stud 90 26 is rotated and the latch 25 moved to 95 operative position.

It is believed that the manner of operation and use of my improved rail fastening means will be readily understood from the above 100 description. By rotating the pinion 28 the latch 25 is moved into engagement with the base flange of the rail, while at the same time the bolt 32 is engaged in the end of the tie-bar 12.

Having thus described my invention what I claim as new and desire to protect by Letters Patent of the United States is as follows:

1. In combination with a pair of track 110 rails, a tie bar having integral flanges at opposite ends adapted to engage the base

- flanges of the rails on one side thereof, and a pair of pivoted latch bars adapted to engage the opposite sides of the said base flanges, and worm and pinion operating means for said latch bars.
2. In combination with a pair of track rails, a tie-bar having integral back-turned flanges at opposite ends adapted to engage the base flanges of the rails on the outer sides thereof, the top face of said tie-bar being recessed between the rails, a supplementary strip filling the recess in the said tie-bar said strip being recessed on its under side, and a pair of latch bars pivoted on opposite ends of said strip and adapted to engage the said base flanges on the inner sides thereof.
3. In combination with a pair of track rails, a tie-bar having integral back-turned flanges at opposite ends adapted to engage the base flanges of the rails on the outer sides thereof, the top face of said tie-bar being recessed between the rails, a supplementary strip filling the recess in the said tie-bar said strip being recessed on its under side, and a pair of latch bars pivoted on opposite ends of said strip and adapted to engage the said base flanges on the inner sides thereof, and worm and pinion means located in the recess in the said strip for operating said latch bars.
4. In combination with a pair of track rails, a tie-bar having integral back-turned flanges at opposite ends adapted to engage the base flanges of the rails on the outer sides thereof, the top face of said tie-bar being recessed between the rails, a supplementary strip filling the recess in the said tie-bar said strip being recessed on its under side, and a pair of latch bars pivoted on opposite ends of said strip and adapted to engage the said base flanges on the inner sides thereof, and means operated in common with the said
5. In combination with a pair of track rails, a tie-bar having integral back-turned flanges at opposite ends adapted to engage the base flanges of the rails on the outer sides thereof, the top face of said tie-bar being recessed between the rails, a supplementary strip filling the recess in the said tie-bar said strip being recessed on its under side, and a pair of latch bars pivoted on opposite ends of said strip and adapted to engage the said base flanges on the inner sides thereof, and means operated in common with the said latches for locking said strip to the said tie-bar, said means comprising bolts slideable in the ends of the said strip, and cam elements rotatable with the latches for moving said bolts to operative position.
6. In combination with a pair of track rails, a tie-bar having integral back-turned flanges at opposite ends adapted to engage the base flanges of the rails on the outer sides thereof, the top face of said tie-bar being recessed between the rails, a supplementary strip filling the recess in the said tie-bar said strip being recessed on its under side, and a pair of latch bars pivoted on opposite ends of said strip and adapted to engage the said base flanges on the inner sides thereof, and means operated in common with the said latches for locking said strip to the said tie-bar, said means comprising bolts slideable in the ends of the said strip, and cam elements rotatable with the latches for moving said bolts to operative position, and springs surrounding said bolts and normally urging the same to retracted position.

In testimony whereof I have affixed my signature.

JOHN ZOTKIEWICZ.
